UNITED STATES PATENT OFFICE.

FRANCIS G. ARTER AND JOHN C. BLOCHER, OF LIMA, OHIO.

CAR-COUPING.

SPECIFICATION forming part of Letters Patent No. 238,325, dated March 1, 1881.

Application filed January 15, 1881. (No model.)

To all whom it may concern:

Be it known that we, FRANCIS G. ARTER and JOHN C. BLOCHER, citizens of the United States, residing at Lima, in the county of Allen 5 and State of Ohio, have invented certain new and useful Improvements in Car-Couplers; and we do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 Our invention relates to improvements in car-couplings; and the object of our invention is to so construct and shape the interior of the mouth of the draw-head of a car-coupler as to perfectly adapt it to admit of certain requisite 20 movements of the inner end of the coupling-link when the latter is adjusted by a link-supporting tongue, and to provide certain other features of improvement specially adapted to overcome objections that have hitherto existed 25 in using link-supporting tongues.

We will now proceed to describe the construction and arrangement of the several features of our invention and explain their operation, and then will designate the same in 30 the claims.

In the annexed drawings, Figure 1 is a vertical longitudinal section of a car-coupler. Fig. 2 is a plan or top view of same. Fig. 3 is a side view of the draw-head. Fig. 4 is a front 35 view of same. Fig. 5 is a perspective of the link-supporter.

The letter A designates the draw-head or buffer, and B its neck or shank, which is connected with the car in the usual or any well-known manner. An ordinary coupling-link, 40 C, and pin D are used.

E designates the link-supporting tongue, which serves to lift and sustain the link, as shown in Fig. 1, and guide it when coupling. 45 The tongue is provided with an eye, by which it is attached to its shaft, which extends in a horizontal direction from side to side. In cross-section the shape of the eye is circular for about three-quarters of its size and straight 50 for the remaining quarter. The part n of the tongue, which constitutes the exterior of the

shaft-eye, is rounded or partly cylindrical, as shown in Figs. 1 and 5, and the lower side of the interior of the mouth of the draw-head is provided with a groove, p, extending cross-wise, serving as a seat or bearing, in which the cylindrical part n of the tongue rests, and wherein it turns as the front of the tongue is raised or lowered. This construction is of importance, since thereby none of the strain, 55 pressure, or weight caused by the coupling-link falls on the rock-shaft, which passes through the eye of the tongue. The said shaft, therefore, will never become bent, and will always be easily turned, serving merely as a means to 60 raise or lower the tongue.

The rock-shaft F has a flattened side, a, extending from end to end, which in width is equal to about one-quarter of its circumference. It will be seen the flattened side of the rock-shaft fits the corresponding part of the eye 70 of the tongue and prevents the latter from turning on the shaft, while the three-quarters-rounded part of the shaft fits within the holes in the sides of the draw-head. These holes 75 (which are not shown in the drawings) are slightly oblong instead of accurately round, the long part being in a vertical direction. The object of this is to prevent the ends of the rock-shaft from bearing within the holes, leaving 80 all pressure of the coupling-link to come on the tongue, the cylindrical part of which sets in the groove p, as before stated. Thus our device is both practical and cheap. It will be seen the front or raising end of the tongue does not 85 project fully to the mouth of the draw-head, but is recessed or wholly within, and is protected thereby from accidental breakage. One or both ends of the shaft are provided with a detachable head, b, which slips over the end 90 of the shaft after the latter has been passed through the draw-head. The head b has an eye, with which a hand-rod, G, is connected by one end, the other end of the rod being adapted to hang down and swing freely, or to be extended 95 horizontally, and thus serves to raise the tongue and support the coupling-link, enabling the person, by grasping the hand-rod, to stand outside of the track while coupling, and thereby avoid the risk of injury which is attended 100 by going between the cars.

By providing at each side of the draw-head

or buffer a horizontally-projecting lug, *c*, the hand-rod *G* may be extended and raised upward, and from the position indicated by dotted lines in Fig. 3, (whereat the tongue is down,) turned upward and back to the position shown in same figure, and rest behind the lug *c*, and thus the hand-rod and lug will sustain the coupling-link at the ordinary height suited for effecting a coupling. The concussion or jar which is occasioned by the bumping of the cars will cause the raised hand-rod to topple over, and thus allow the tongue to fall.

In order to support the coupling-pin at an elevated position to admit into the mouth of the draw-head the coupling-link of an opposite draw-head, we provide a notch, *u*, which extends about three-fourths of the way around the coupling-pin hole—that is, on its front and two sides. When the cars come together the concussion will cause the pin to drop and pass through the link.

When coupling it is necessary to hold the extended end of the coupling-link in a direction straight forward, so that it will enter the mouth of the opposite draw-head. This is effected by providing each side of the tongue *E* with a raised edge, *d*, which slopes down toward the center of the tongue. If the end of the coupling-link be turned a little to one side when the tongue is brought up against it, the raised sloping edge of the tongue will cause the link to slide to the center of the tongue, and thus point the link straight forward.

While tongues to support and adjust the coupling-link have heretofore been shown and described in patents, no such device has yet found acceptance with railroad managers, and consequently none are in practical use, which we attribute to the fact that the devices were crude and impracticable, and that proper provision has not been made for certain requisite movements of the inner end of the coupling-link.

By reference to Fig. 1 of the drawings, it will be seen we have so contrived the interior shape of the mouth of the draw-head that the highest part of the tongue—the rounded part over the eye through which the rock-shaft passes—forms a bearing, *e*, on which the coupling-link may rest. Both in front of and behind this lower bearing the interior of the draw-head is lower than the bearing.

The letter *g* designates the lower space within the draw-head behind the lower bearing, *e*. Upon the interior upper side of the draw-head is a downward-projecting point, *f*, which extends in a horizontal line crosswise of the draw-head. From this point *f* the roof or upper side of the draw-head extends upward in front and behind in a straight line, forming in front a flaring mouth and behind an upward-extending space, *h*, corresponding to the space *g* below. From the highest point of the upper space, *h*, to the lowest point of the lower space, *g*, the rear wall of the interior

is in the form of a curve, *i*. The point *f*, projecting downward, forms an upper bearing for the coupling-link, which, in practice, is about one and a quarter inch back from the lower bearing, *e*, and is in front of the coupling-pin.

When the tongue is raised by turning the hand-rod the coupling-link is lifted, and its upper side rests against the upper bearing, *f*, while the inner end of the link may move vertically in the direction of an arc of a circle to an extent which is limited only by the size of the rear spaces, *g h*. This provision for the movement of the inner end of the coupling-link with the upper bearing, *f*, to hold the link down to the tongue enables the latter to adjust and control the outer or extended end of the link in the most perfect manner, and thereby our link-supporting tongue becomes a practically operative device, free of the objections which hitherto existed.

Having described our invention, we claim and desire to secure by Letters Patent of the United States—

1. In a car-coupling, the combination of a rock-shaft extending horizontally through the draw-head with its ends projecting at each side, a link-supporting tongue in the mouth of the draw-head, and a hand-rod, *G*, movably secured to the end of the rock-shaft, whereby the hand-rod may hang down and swing freely or be extended horizontally in a line direct with the axis of the rock-shaft, as and for the purpose set forth.

2. In a car-coupler having a link-supporting tongue, the combination, with the draw-head, of a horizontally-projecting lug, *c*, at either side and a hand-rod attached to the ends of the rock-shaft, adapted, when resting behind the lug, to sustain the coupling-link, as set forth.

3. The improved link-supporting tongue for a car-coupling, having at each of two sides a raised edge, *d*, which slopes down toward the center of the tongue, as set forth.

4. In a car-coupler, the combination, within the mouth of the draw-head, of a tongue, *E*, to lift and sustain the coupling-link, an upper bearing, *f*, projecting down from the roof of the mouth, extending crosswise thereof, and located back from the tongue, and a coupling-pin hole back of both tongue and bearing, as set forth.

5. In a car-coupler, the combination of a link-supporting tongue having on its under side a rounded pivotal bearing, *n*, and the draw-head having a corresponding-shaped groove, *p*, in which the rounded part rests, as set forth.

In testimony whereof we affix our signatures in presence of two witnesses.

FRANCIS G. ARTER.
JOHN C. BLOCHER.
